UNITED STATES PATENT OFFICE.

ALBERT RAYMOND, OF CHICAGO, ILLINOIS.

PNEUMATIC SEPARATOR.

SPECIFICATION forming part of Letters Patent No. 687,266, dated November 26, 1901.

Application filed October 9, 1899. Serial No. 733,004. (No model.)

To all whom it may concern:

Be it known that I, ALBERT RAYMOND, a citizen of the United States, residing in the city of Chicago, Cook county, and State of Illinois, have invented a new and useful Improvement in Pneumatic Separators, of which the following is a specification.

My invention relates to that class of separators employed for extracting the finer from the coarser particles of various pulverized materials, as ores, marble, gypsum, cements, sand, coal, &c., in which a diminishing force of an air-current acts against gravity; and my invention relates particularly to a separator of this class for which Letters Patent were granted to myself and George Raymond April 6, 1897, bearing No. 580,145. In this patent it is shown that the diminishing force of an air-current is produced by placing one inverted hollow cone within another, leaving a space between them, whereby the intensity of an induced upward current of air between them is diminished in proportion to the taper of the cones and the consequent increase of space the air will occupy as it is drawn up between the cones. As the mixed material—that is, the finer and coarser particles of the pulverized substances—are carried by the induced current of air up between the said cones the coarser particles, because of their greater specific gravity, immediately begin to fall back and the finer particles pass on and are drawn off, so that before the material reaches the top of the cones the air-current becomes so diminished that all the coarser material will have fallen back into the pulverizer and only that of sufficient fineness will have passed over and out of the separator.

Having thus stated the general operation of the patent above alluded to, it will make more apparent the object of my present improvement, which is to render more effective my former device, which I accomplish by the mechanism illustrated in the accompanying drawings, in which—

Figure 1 is an elevation representing the separator above mentioned and my present improvement added; Fig. 2, a view looking downward, showing my improvement and a partial view of the separator alluded to, and Fig. 3 a plan view of my improvement.

1 is the outer cone-shaped shell; 2, the inner cone-shaped shell; 3, the space between the said shells; 4, the cover of the conic shells, 55 from which extends a conical deflector 5, extending slightly below the top of the outer cone and which may be made adjustable.

6 is a suction-pipe with a flared opening 6^a at the top; 7, a fan-blower that creates the 60 suction and induced current of air which draws the finished product from the separator and discharges it into the dust-collector 8, which may be of the cyclone, centrifugal, or any other type. The air in the dust-collector 65 as it becomes free of the product is again returned to the separator through the pipe 10, and the finished product falls out of the bottom of the collector through a trap-discharge 9.

12 is a stack or throat into which is fed the 70 material to be separated through the feeding-pipe 11, the feeder 11^a being worked by the belt 11^b. The tailings of the separator fall from the stack 12 through the spout 13 back into the pulverizer, which is not shown. 75

14 and 14^a represent floors of the building in which the separator is installed.

The separator as far as above described is covered by the Patent No. 580,145, heretofore mentioned, and I will now point out and 80 describe my present improvements.

15 and 15^a represent horizontal fan-wheels, the blades *a* of which stand at an angle with the horizontal plane. These fan-wheels are mounted at suitable distance apart, within 85 the throat of the separator, on the shaft 16, which said shaft is actuated at high speed by any suitable means. By the rapid rotation of these fan-wheels certain useful results are attained—first, they thoroughly agitate, divide, and scatter the material within the stack 12; second, they throw the material upward mechanically and by an upward current of air they create, and, third, they cause the induced ascending current of air between the 90 outer and inner cones of the separator to take a spiral motion, as indicated by arrows in Fig. 1, which causes the material to travel a greater distance before it reaches the mouth of the pipe leading to the dust-collector than 100 if it ascended directly upward between the conic shells, thereby affording an increase of time for gravity to act upon the coarser particles before they ascend to the top of the said

shells, which prevents them from passing over with the finer portion. To further increase this whirling or spiral movement of the ascending current of air and the material it carries with it in the space inclosed between the inverted-cone-shaped shells, I provide a tangential inlet to the throat of the separator, through which passes into the said throat the return air-current from the dust-collector. 5 (Best shown in Fig. 3.) This tangential inlet into the throat 12 of the separator, together with the action of the horizontal fan-blowers 15 and 15^a, as above explained, create such a powerful spiral action of the air-current and material to be acted upon that in practice I find it makes the same separator far more efficient. 10

Having described my improvement and explained its operation, what I claim as new and 15 useful, and desire to secure by Letters Patent, is—

1. In a pneumatic separator the combination of a tangential inlet in the throat thereof and horizontal fan-blowers in the said throat 20 having blades set at an angle with the horizontal plane, means for feeding material upon the upper surface of said fan and any suitable means for rapidly rotating said blowers, whereby the material fed to said fans is agi- 25

tated, separated and thrown upward into the 30 separator by said fans, substantially as and for the purpose set forth.

2. In the throat of a pneumatic separator, having two inverted-cone-shaped shells placed one within the other inclosing an air-passage 35 between them, the combination of a tangential inlet and horizontal fan-blowers having blades set at an angle with the horizontal plane and having any ordinary means of rapid rotation, and means for feeding the material 40 to be separated directly to said fan-wheels, substantially as described.

3. In a pneumatic separator, having two inverted-cone-shaped shells placed one within the other inclosing an air-passage between 45 them, the combination with the throat thereof of one or more horizontal fan-wheels having blades set at an angle with the horizontal plane and any suitable means of rapidly rotating said fan-wheels within the said throat, 50 and means for feeding the material to be separated directly to said fan-wheels, for the purposes set forth.

ALBERT RAYMOND.
